UNITED STATES PATENT OFFICE.

GEORGE R. HENDERSON AND WILLIAM I. CANTLEY, OF PHILADELPHIA, PENNSYLVANIA, ASSIGNEES, BY MESNE ASSIGNMENTS, TO LOCOMOTIVE SUPERHEATER COMPANY, OF WILMINGTON, DELAWARE, A CORPORATION OF DELAWARE.

SUPERHEATER.

1,142,254.

Specification of Letters Patent.

Patented June 8, 1915.

Application filed September 27, 1911. Serial No. 651,501.

To all whom it may concern:

Be it known that we, GEORGE R. HENDERSON and WILLIAM I. CANTLEY, citizens of the United States, residing in Philadelphia, county of Philadelphia, State of Pennsylvania, have invented certain Improvements in Superheaters, of which the following is a specification.

This invention relates to certain improvements in superheaters of the type having superheater elements or pipes which extend into the tubes of a boiler.

The invention is particularly adapted to boilers of the locomotive type, in which one part of the superheater is located in the smoke box and the superheater elements forming the other part extend into the flue tubes of the boiler.

One object of this invention is to construct the superheater so that any of the superheating elements can be removed without removing any other superheating elements or dismantling the superheater and so that, when one element has been detached, the tube of the boiler into which its pipes extend can be removed without detaching any of the other elements or the header.

A further object of the invention is to construct the header to which the superheating elements are connected in such a manner that its alternate columns will communicate with the top of the superheater and the other columns will connect with the bottom of the superheater.

A still further object of the invention is to provide means for readily and firmly securing each circulating pipe to the main header.

In the accompanying drawings:—Figure 1, is a longitudinal sectional view of sufficient of a locomotive boiler to illustrate our invention, the section being on the line 1—1, Fig. 2; Fig. 2, is a transverse sectional view on the line 2—2, Fig. 1; Fig. 3, is an enlarged sectional plan view on the line 3—3, Fig. 2; Fig. 4, is an end view of one of the pipe heads; Fig. 5, is a sectional view on the line 5—5, Fig. 3; Fig. 6, is a sectional view on the line 6—6, Fig. 1, showing a portion of the header with the pipe heads removed; Fig. 7, is a perspective view of the header; Fig. 8, is a perspective view of the heads of one superheater element; and Fig. 9, is a

perspective view of the wedge used for attaching the pipe heads to the header.

A is the shell of a locomotive boiler, in the present instance having a tube sheet *a* separating the main body of the boiler A' from the smoke box A².

*a*², *a*² are the ordinary flue tubes of the boiler and *a'*, *a'* are flue tubes of greater diameter into which the pipes of the superheater elements extend.

B is the superheater consisting of a header located in the smoke box of the boiler and having superheater elements or circulating pipes *i* which extend into the large flue tubes of the boiler to any extent desired.

A superheater of this particular type is old and our invention, as before remarked, relates to a particular construction of superheater, which we will now proceed to describe.

D is the header which is located in the smoke box. This header is made in the manner clearly illustrated in the perspective view, Fig. 7, and has an upper manifold *d* and a lower manifold *d'* united by alternately disposed hollow columns *c*, *c'*. The columns *c'* are closed at their upper ends and communicate at their lower ends with the lower manifold *d'*. The alternate columns *c* are closed at their lower ends and communicate at their upper ends with the upper manifold *d*. This upper manifold in turn communicates, through a pipe C, with the pipe C' leading from the steam space of the boiler. The lower manifold *d'* has an opening *d*² at each end and is coupled to the pipes D' leading to the steam ports of the cylinders. These pipes may communicate with the pipes leading to the cylinder, either through the bottom of the smoke box or through the side, as desired. Mounted in the space between the alternate columns *c*, *c'* are the pipe heads E to which the superheating elements *i* are connected. The heads are made in the form illustrated in Fig. 8, and the end of the pipes *i* are screw threaded, as illustrated in Fig. 3, and are screwed into the threaded openings *e* of the heads. The heads may be made in a single piece and completely finished, then severed, as illustrated in Fig. 8.

The openings *e* with which the pipes *i* communicate connect with transverse openings

e', and these openings are in such a position in the header, as illustrated in Fig. 3, as to align with the openings *c²*, *c³*. The openings *c²* are in the walls of the columns 5 *c*, while the openings *c³* are in the walls of the columns *c*. The other inner ends of the pipes *i* are connected by a coupling *i'* formed, as illustrated in Fig. 1, so that the steam will pass from the columns *c*, through 10 the openings or passages *c³*, *e'* and *e*, then through a pipe *i*, coupling *i'* and return through the other pipe *i* and into the columns *c'*; the steam being superheated as it travels through the pipes which extend into 15 the flue tubes *a'*, as the products of combustion come in direct contact with the said pipes.

The heads of the superheater sections are secured to the main header in the following 20 manner:—Each head has a projecting rim *e²* which extends into one of the openings *c²* or *c³* of the main header, and located in an annular groove surrounding the said opening is a copper ring *h*, in the present instance, forming a gasket which, when the 25 heads are spread apart, makes a steam tight joint between the heads and the header.

In order to force the heads apart, we provide a bolt *N* with a conical wedge *M* which 30 is adapted to be inserted into a conical opening *m*; part of said opening being in one head and part in the other head as illustrated in Fig. 8. The head *n* of the bolt rests against the large end of the wedge and 35 the threaded end of the bolt screws into a nut *n'*, which is held from turning by being shaped so as to partly encircle the circulating pipes *i*, *i*, Fig. 5.

When assembling the parts, the pipes are 40 attached to the head *E*, *E* and connected together by the couplings *i'*. The heads *E*, *E* are then located in one of the channels between the columns, *c*, *c'* of the header *D* and the bolt *N* with the wedge *M* is passed 45 through the opening *m* between the heads and the nut is placed in position and the bolt turned so as to force the wedge into the opening, spreading the heads *E*, *E* apart and against the columns of the header *D*. 50 When it is necessary to detach one of these sections the bolt *N* may be unscrewed from the nut *n'* so as to permit the wedge *M* to be removed and allowing the heads to come together so that the projections *e²* will clear 55 the columns of the header, after which the two heads with the pipes attached can be readily removed from the opening in the header.

In the drawings, we have shown two superheating elements in each flue tube and we have staggered the heads to which these elements are connected, so that the heads of the lower element are attached near the outside of or from the header while the 60 heads of the upper element are attached 65

near the inner or rear side. The location of these heads may be varied without departing from the essential features of the invention.

If it is desired to make a series of four superheating pipes for each pair of heads, 70 then there will be only one set of four pipes located in each tube, and there will be only one row of heads, which will not be staggered.

In the construction shown in the drawings, 75 if the two superheater elements are removed from one of the tubes of the boiler, then this tube of the boiler may be removed, if necessary, without disturbing the other superheater elements, although, in some instances, it may be desirable to remove more than two superheater elements if more freedom for removing the boiler tubes is desired.

The header *D* is mounted on brackets *s*, *s* 80 secured to each side of the casing of the smoke box section of the boiler, and it is also suspended by rods *s'* from the top of the smoke box section; the header being shaped as illustrated in Fig. 7 to allow for 85 this method of attaching, but it will be understood that other means for attaching the superheater to the boiler may be resorted to without departing from the main features of the invention. 90

We claim:—

1. The combination in a boiler having a smoke box and tubes, of a superheater having a header mounted in the smoke box and pipes extending from the header into the tubes, the header having a manifold at the top and bottom and a series of columns spaced apart, said columns being hollow, the alternate columns connecting with the upper manifold and the other columns connecting 105 with the lower manifold, with a head on the end of each pipe, said heads being located in the space between the two columns, and means for forcing the heads apart and against the columns so as to make a steam 110 tight joint between the heads and the columns.

2. The combination in a boiler, of a series of flue tubes, a superheater having a series of pipes extending into the flue tubes, a header 115 having a series of spaced hollow columns and upper and lower manifolds, the alternate columns being connected to the upper manifold and the other columns to the lower manifold, said columns having furthermore openings in 120 their side walls, and the pipes having heads located within the space between the columns and connected to the openings of said columns, the upper manifold being connected to the steam space of the boiler and the lower manifold being connected to the steam chests of the cylinders.

3. The combination in a superheater, of a locomotive boiler having a smoke box and flue tubes, a superheater having a header 130

- located in the smoke box of the boiler and made of a single casting and having spaced tubular columns, manifolds at the top and bottom, the upper manifold connecting with alternate columns and the other manifold connecting with the other columns, a series of pairs of heads mounted in the space between the columns, means for separating the heads and for forcing them against the walls of the columns, with pipes secured to each head and extending into a flue tube of the boiler, said pipes being connected at their outer ends so that the steam will circulate in its passage through the superheater.
4. The combination in a boiler having a smoke box and a series of flue tubes, of a superheater having a header located in the smoke box and having vertical hollow columns spaced apart, with upper and lower manifolds, the upper manifold connecting with alternate columns and the lower manifold connecting with the other columns, the side walls of each column having openings therein, heads mounted in the space between the columns and arranged to align with the openings in the walls of the columns; means for securing the heads to the columns, and a circulating pipe attached to each head and extending into the flue tubes of the boiler, said circulating pipes being connected so that the steam will circulate therethrough, as it passes from the steam space of the boiler to the cylinders.
5. The combination in a superheater, of a header having columns spaced apart, one for saturated steam and the other for superheated steam, there being an opening in the side of each column, superheating pipes, a head secured to each pipe, said pipes being connected, one head being arranged in line with an opening in one column and the other head being arranged in line with the opening in the other column, means for forcing the heads apart, and rings forming a steam tight joint between the heads and the columns.
6. The combination of two hollow columns, the side walls of each column having openings therein, one of said columns being for saturated steam and the other for superheated steam, circulating pipes connected at their outer ends, a head on each circulating pipe, said heads having openings adapted to align with the openings in a column, a bolt located between the two heads, and a wedge on the bolt, so that on turning the bolt the wedge will force the heads apart and against the sides of the columns.
7. The combination in a boiler having a smoke box and flue tubes, of a superheater consisting of a header made of a series of hollow columns and upper and lower manifolds, the columns having two sets of lateral openings, said openings being staggered; two sets of circulating pipes located in each flue; a head on the end of each pipe and located between the columns; means for forcing the heads of the circulating pipes against the columns of the header, the pipes of each set being connected at their outer ends, the heads of one series of pipes being attached to the header near the rear thereof and connected with one series of openings, and the heads of the alternate series of pipes being attached to the header near the front thereof and connected to the other series of openings, whereby a number of pipes can be placed close together without one set of heads interfering with the other set.
8. The combination in a superheater, of a header having passages spaced apart, one for the saturated steam and the other for the superheated steam, the side walls of the header having openings therein, circulating pipes connected at one end and having separate heads at the other end, said heads being mounted in the passages of the header, each head having a right angled passage forming communication between the pipe and the passage, there being a conical opening formed between the two heads, a conical wedge mounted in the said opening, a bolt extending through the wedge, with a nut located between the tubes of adjacent heads whereby they are prevented from turning so that on turning the bolt the wedge will be forced into the space between the two heads and will cause the heads to bind against the walls of the sections forming the passages.
9. The combination in a locomotive, of a boiler having a smoke box and a series of flue tubes communicating with the smoke box, one set of flue tubes being of greater diameter than the other set, a superheater consisting of a header and circulating pipes, the header being mounted in the smoke box of the boiler and the circulating pipes extending into the flue tubes of large diameter, the header being made up of a series of hollow columns and manifolds at the top and bottom, the upper manifold being connected to alternate columns and the lower manifold being connected to the other columns, a head on the inner end of each pipe, means located between the heads for forcing the said heads apart and against the walls of the columns of the header, the outer ends of the pipes being connected, a steam pipe leading from the steam space of the boiler, the upper manifold being connected to said steam pipe, and steam pipes leading to the cylinders of the boiler of the locomotive and communicating with the manifold, so that the steam as it comes from the boiler is passed through the circulating pipes, which come in direct contact with the products of combustion passing through the boiler.
10. The combination in a locomotive boiler having a tube sheet and horizontal flue tubes

and also having a smoke box section, with a superheater having a header located within the smoke box in front of the sheet, and having through passages, circulating pipes extending into the flue tubes and having heads located in the through passages and connected laterally with the header, of means for coupling the heads of the circulating pipes to the header, said means being accessible through the passages in the header.

11. A header for a superheater made in a single casting and having spaced hollow columns, with a manifold at the top and a manifold at the bottom, the upper manifold being connected with alternate columns and the other manifold being connected with the other columns.

12. The combination in a boiler, of a series of flue tubes, a header having a plurality of spaced hollow columns and upper and lower manifolds for wet and superheated steam respectively, the alternate columns being connected to the upper manifold and the other columns to the lower manifold said columns having, furthermore, openings

in their side walls, and a plurality of superheated elements extending into the flue tubes the ends of each element being connected to openings in adjacent columns.

13. The combination in a boiler, of a series of flue tubes, an integral cast header having opposite manifolds for wet and superheated steam respectively and connected by a series of spaced hollow columns, alternate columns being connected to one manifold and the remaining columns to the other manifold said columns having furthermore, openings in their side walls, and a plurality of superheater elements extending into the flue tubes the ends of each element being connected to adjacent walls of neighboring columns.

In testimony whereof, we have signed our names to this specification, in the presence of two subscribing witnesses.
